PUTTER GOLF CLUB GRIP

Victor L. Dworak, Huntington Beach, and John J. Baker,
Laguna Hills, Calif., assignors to AMF Incorporated

Filed Apr. 1, 1969, Ser. No. 16,543

Term of patent 14 years

Int. Cl. D21—03

U.S. Cl. D34—5

FIG. 1

FIG. 2

FIG. 4

FIG. 3

FIG. 1 is a top plan view of a putter golf club grip having our design;

FIG. 2 is a side elevation view thereof;

FIG. 3 is an end view thereof when viewed from along the section line 3—3 of FIG. 2;

FIG. 4 is an opposite end view thereof when viewed from along the section line 4—4 of FIG. 2;

FIG. 5 is a bottom plan view of the putter golf club grip; and

FIGS. 6A through 6K comprise a series of sectional views along the length of the grip and are taken along the lines 6A—6A through 6K—6K respectively.

We claim:

The ornamental design for a putter golf club grip, substantially as shown.
